UNITED STATES PATENT OFFICE.

LAWRANCE STEPHENS, OF ST. LOUIS, MISSOURI, ASSIGNOR OF TWO-THIRDS TO ALSTON L. RYLAND, OF SAME PLACE, AND CHARLES D. MOODY, OF WEBSTER GROVES, MISSOURI.

SHOE-NAIL.

SPECIFICATION forming part of Letters Patent No. 377,503, dated February 7, 1888.

Application filed October 15, 1887. Serial No. 252,471. (No model.)

To all whom it may concern:

Be it known that I, LAWRANCE STEPHENS, of St. Louis, Missouri, have made a new and useful Improvement in Shoe-Nails, of which 5 the following is a full, clear, and exact description.

The particular shape of the nail, especially of that portion thereof which may be considered the head, is the feature of the improvement.

The annexed drawings, making part of this specification, exhibit the improved nail and the mode of applying it.

Figure 1 is a view in perspective of the improved nail. Fig. 2 is a view in perspective, showing the form of the blank from which the nail is made. Fig. 3 is a bottom view of a shoe-heel having the improved nails applied thereto. Fig. 4 is a cross-section on the line 4 4 of Fig. 20 3. Fig. 5 is a section similar to that of Fig. 4, but showing the nail-heads projecting from the heel.

The same letters of reference denote the same parts.

25 A represents the improved shoe-nail. Its head a , or that portion of the nail which extends laterally to its body a' , instead of being of uniform width, is wider at its outer end, a^2 , than where it unites with the body a' , and the 30 head extends to one side only of the body. The improvement is carried out more perfectly by making the head a to taper from its outer end, a^2 , to its junction with the body a' , and by tapering the body also, substantially as 35 shown in Fig. 1. By making the head thus wider at its outer end a form of nail is obtained which is especially useful for a certain class of shoes. The nails, as illustrated in Fig. 3, can be so applied to the shoe-heel B, 40 and also to other parts of the shoe, as to provide a continuous metallic protection for the heel at its outer edge, and also to cause the nails, by reason of their heads being laid to-

gether, to brace each other, so that any strain received by a nail-head is transmitted to and 45 sustained by all the adjacent nail-heads and nails. To this end the nails may be shaped and combined as shown at b , or as shown at b' , Fig. 3; but when combined as at b the body a' of the nail should taper, as shown, 50 as otherwise the leather or substance of the heel is cut away continuously by the insertion of the nails; but when the nails are combined as shown at b' , or when only the outer end of the nail-head is widened, the necessity 55 of tapering the nail-body is not so apparent. It is, however, better in all cases to taper the nail-body, as thereby the heel, where the nails are inserted, is less liable to be cut continuously, and the nails, in consequence, are more firmly 60 held in place. The precise form of nail shown—namely, one tapering from the outer end of the nail-head to the point of the nail-body—is, further, a desirable one, in that the blank C, Fig. 2, from which the nail is made, in turn 65 can be readily and economically prepared from a metallic plate.

The present nail can be used upon boots as well as shoes, and, while especially adapted to shoes and boots, it can be used for other 70 purposes.

I claim—

1. The herein-described shoe-nail formed of a single piece of metal, tapering as described, its head bent at right angles to the body, and 75 wider at the outer end than where it unites with the nail-body.

2. The combination of the nails A, each having its head a widest at its outer end, a^2 , and bent at right angles to the tapering body a' , 80 with the heel B, whereby the heel is provided at its outer edge with a metallic protection.

LAWRANCE STEPHENS.
